UNITED STATES PATENT OFFICE.

ROLAND B. RESPESS, OF NEW YORK, N. Y., ASSIGNOR, BY MESNE ASSIGNMENTS, TO
RESPRO INC., OF CRANSTON, RHODE ISLAND, A CORPORATION OF RHODE ISLAND.

PROCESS OF MAKING ARTIFICIAL LEATHER.

Application filed May 21, 1920. Serial No. 383,222.

To all whom it may concern:

Be it known that I, ROLAND B. RESPESS, citizen of the United States, and resident of the borough of Manhattan, city of New York, in the county of New York and State of New York, have invented certain new and useful Improvements in Processes of Making Artificial Leather, of which the following is a specification.

This invention relates to a process of making artificial leather, and its special object is an improved method of applying surface dressing to woven cloth or felted fabric. With this invention there is obtained greater adhesion and durability for the surface dressing than is obtained by passing woven fabric or felted sheet under a knife, as now employed in coating woven fabric or felt with liquid cellulose compound or other leather surface dressings. This method may also be employed to obtain better results in filling the small openings termed pin holes which occur in nearly all coated fabrics where the knife method alone is used. I desire to cover the application only of liquid surface coating like a cellulose compound and not to apply to the application of heavy, doughy compounds like rubber, which may be applied with pressure

calender rolls.

Various means and methods may be employed to apply the coating solution to the fabric, and in the accompanying drawings Fig. 1 shows a longitudinal section of the artificial leather; Figs. 2 and 3 represent diagrammatic views of apparatus to produce the artificial leather.

In Fig. 1 a sheet of woven or felted fabric 10 is indicated with a surface dressing 12. The latter is preferably a cellulose compound which may consist of commercial liquid cellulose mixed with boiled linseed oil or castor oil.

In Fig. 2 a shaft 15 is journaled in housings like 16. A tensioning device comprises the lower member 20, which bears up against the shaft 15 and has formed therewith the lug 21 and the arm 22. The lug 21 is fastened to one of the housings 16, by means of screws 23. An upper member 25 having the arm 26 is hinged to the lower member 20. A bolt 28 connects the arms 22 and 26 and thereby pressure can be brought on the shaft 15 to regulate its speed of rotation. The members 20 and 25 with their appurtenances

constitute a tension device. A block 32 has adjustably supported thereon the supporting table 33. A guide roller 35 is journaled on one side of the table 33, and a pair of guide rollers 36 and 37 are journaled on the other side of said table. A friction roller 40 is journaled above the rollers 36 and 37. Driving rollers are indicated at 42 and 43. A tank 45 for the liquid cellulose compound has extending therefrom the outlet nozzle 46 with the regulating valve 47. An adjustable knife or smear blade is indicated at 48.

In Fig. 3 are indicated a pair of presser rollers 52, 53, with the fabric 10 and a plurality of coatings constituting the surface dressing thereon.

To produce the artificial leather the fabric is unwound from the shaft 15, under the control of the tension device having the members 20, 25 and passes over the guide roller 35, the table 33, then under the knife 48. The fabric next passes over the guide roller 36, under the friction roller 40 and over the guide roller 37. Then the coated sheet passes under tension to contact with the fast revolving friction roller 40, where the liquid is pressed by friction into the fibers of the sheet.

The liquid cellulose compound 12 issues from the nozzle 46 and is deposited upon the fabric 10 and properly spread thereon by the knife 48. Next the friction roller 40 frictions the liquid compound into the fabric. The fabric with its coating constituting the surface dressing is propelled through the apparatus by the rollers 42, 43 and then dried. The rollers 42 and 43 may be omitted and the fabric propelled by other means.

The fabric with its coating may be subjected to the same steps, a plurality of times to deposit thereon a number of layers of the coating or surface dressing one over the other, and in such a case the fabric 10 with its plurality of layers 12 of surface dressing is passed between the pressure rollers 52 and 53 to form a thick compact coating or surface dressing for the fabric.

Fabric coated in the manner described will be found to hold the surface dressing firmly thereto by reason of a part of the dressing penetrating into the twisted fibers of the woven sheet or the matted felted sheet and the coating being better attached to the surface of the sheet, than by use of a knife.

alone and will have less tendency to crack or peel and produces a more durable surface.

Having described my invention, what I desire to secure by Letters Patent and 5 claim is:

The herein described process of coating a fabric with a liquid surface dressing consisting in maintaining the fabric under tension, depositing a liquid cellulose dressing 10 on the fabric, spreading the dressing, fric-

tioning the dressing into the fabric, repeating the above steps with the same fabric a number of times to deposit a plurality of coatings of the dressing on the fabric one over the other and subjecting the fabric 15 with its coatings to pressure.

Signed at Boston in the county of Suffolk and State of Massachusetts this 12th day of May A. D. 1920.

ROLAND B. RESPRESS.
